(57) **CLAIM**

We claim the ornamental design for a fuel cap, as shown and described.

DESCRIPTION

FIG. 1 is a front perspective view from above of a fuel cap showing our new design.

FIG. 2 is a rear perspective view from above of the claimed design of FIG. 1;

FIG. 3 is another front perspective view from above of the claimed design of FIG. 1;

FIG. 4 is a top view of the claimed design of FIG. 1;

FIG. 5 is a front view of the claimed design of FIG. 1;

FIG. 6 is a left side view of the claimed design of FIG. 1;

FIG. 7 is a right side view of the claimed design of FIG. 1;

FIG. 8 is a rear view of the claimed design of FIG. 1; and,

FIG. 9 is a bottom view of the claimed design of FIG. 1.

In the drawings, the broken lines shown in the Figures depict unclaimed subject matter only and form no part of the claimed design.

1 Claim, 5 Drawing Sheets
